UNITED STATES PATENT OFFICE.

ANDREW J. NEAFIE, OF BOONTON, NEW JERSEY.

RAIL-JOINT.

1,074,972.

Specification of Letters Patent.

Patented Oct. 7, 1913.

Application filed December 12, 1912. Serial No. 736,273.

To all whom it may concern:

Be it known that I, ANDREW J. NEAFIE, a citizen of the United States, residing at Boonton, in the county of Morris and State 5 of New Jersey, have invented a certain new and useful Improvement in Rail-Joints, of which the following is a specification.

The invention relates to insulated joints for supporting and connecting the abutting 10 ends of railway rails, and the object of the invention is to provide a joint of simple and economical construction, easily assembled and installed, by which the rail-ends shall be strongly joined, and reliably insulated 15 from each other.

The invention consists in certain novel features of construction and arrangement of parts, by which the above objects are attained, to be hereinafter described.

20 The accompanying drawings form a part of this specification, and show preferred forms of the invention as it has been carried out in practice.

Figure 1 is a plan view of the improved 25 joint. Fig. 2 is a corresponding side view. Fig. 3 is a vertical longitudinal section, partly in elevation, taken on the line 3—3 in Fig. 4, and Fig. 4 is a transverse section partly in elevation, taken on the broken line 30 4—4 in Fig. 1. Fig. 5 is a plan view of the base-plate for the joint; Fig. 6 is a plan view of a shim or filling-piece therefor, and Fig. 7 is an edge view of the shim. Fig. 8 is a central longitudinal vertical section 35 through the base-plate, on the line 8—8 in Fig. 5. Fig. 9 is a plan view of a modified form of the base-plate, and Fig. 10 is an edge view thereof. Fig. 11 is an edge view of a shim to be used with such modified 40 base-plate. Fig. 12 is an end elevation of an insulating bushing, and Fig. 13 is a corresponding diametrical section.

Similar letters of reference indicate like 45 parts in all the figures.

A and B are abutting rail-ends, shown as of standard type with the usual base-flanges A¹, B¹, and C is a base-plate, preferably of steel, of sufficient length to underlie and support the rail-ends, and adapted to be fastened to a tie, not shown, by lag-screws D or other fastening means extending through holes c¹ in the side margins of the plate. At one end of the plate is a shallow depression or recess c of a width a little greater than 55 the base-flange B¹ of the rail B and extend-

ing a short distance beyond the transverse center line of the plate, or beyond the abutting line of the rail-ends, and E is a filling-piece or shim, preferably of hard wood, shaped to match to and fill the recess flush 60 with the remaining upper face of the plate. A wooden pin E¹ projecting downwardly from the under face of the shim is received in a hole c² in the recess and serves to locate the shim properly and to hold it in position 65 in the recess. Along each side margin of the plate C, in addition to the holes c¹ for the lag-screws, is a series of holes c³ drilled and tapped to receive short stud-bolts F serving to hold the horizontal flanges G¹ of the L- 70 shaped angle-plates G to the base-plate. These angle-plates extend longitudinally, one on each side of the base-plate with their flanges G vertical and parallel with the rail-ends. 75

H, H¹ are check-pieces of hard wood shaped on their inner faces to match to the adjacent side surfaces of the rail, with their outer faces plane and vertical, extending across the rail-joint and received between 80 the rails and vertical flanges G of the angle-plates.

The webs of the rail-ends are bored through at a and b to receive transverse bolts J J which extend through the angle-plates G and cheek-pieces H, H¹, and by the nuts J¹ J¹ thereon bind these parts firmly together and to the abutting rail-ends. The holes in the angle-plates are larger than required for the reception of 90 the bolts J and receive annular bushings K of fiber or other suitable insulating material which serve to insulate the bolts from the angle-plates. The outer faces of the bushings are protected by washers K¹. The 95 recess c and the shim E therein are wider than the base of the rail B to insure against electrical contact of the rail-flange with the base-plate at the sides, and extend longitudinally beyond the end of the rail B and 100 a short distance beneath the rail-end A to insure insulation at the extreme end of the rail. Thus constructed the rail-ends are insulated from each other and both are firmly joined and supported. The abutting ends 105 of the rails are separated as usual by insulating end-posts L of indurated fiber or other suitable material.

By providing the recess c to receive the 110 shim, the correct position of the latter be-

neath the rail-end is insured, aided by the pin E¹ in engagement with the plate, and the whole forms an eminently efficient joint in which the parts are securely held against 5 accidental displacement.

In Figs. 9, 10 and 11 a base-plate C¹ is shown, of modified form, having a raised portion C² formed integral with the plate at one end. The remaining central part of 10 the plate receives a shim E² corresponding in thickness to the raised portion, and held in position by a pin E³ received in a hole e⁴, and serving to insulate one rail-end from the plate as before. The angle-plates, cheek- 15 pieces, and other portions, not shown, for this form of the joint, may be understood to be similar to those above described and to serve in the same manner.

Other modifications may be made in the 20 forms and proportions of the parts as may be found necessary or desirable in adapting the invention to various types of rails or other conditions of service.

I claim:—

25 1. In a rail-joint, a base-plate having the upper face at one end of its central longitudinal portion higher than the other and integral with such plate, and having a hole in the lower portion, a shim of insulating material applied upon such low portion and extending beyond the line of abutment of the rail-ends, a pin of insulating material rigid with and extending from the lower face of said shim and engaged in said hole, 30 angle-plates secured to said base-plate at the side margins of the latter, insulating cheek-pieces between said angle-plates and sides of such rail-ends, bolts extending transversely through said angle-plates, 35 cheek-pieces and rail-ends, and annular in- 40

sulating bushings in said angle-plates for receiving said bolts.

2. In a rail-joint, a base-plate having a recess at one end extending longitudinally thereof beyond the line of abutment of the 45 rail-ends, means rigid with and depending from said shim and extending through the base plate to hold the shim against movement, a shim of insulating material matching to and received in said recess, angle- 50 plates secured to said base-plate at the side margins of the latter, insulating cheek-pieces between said angle-plates and sides of such rail-ends, bolts extending transversely through said angle-plates, cheek- 55 pieces and rail-ends, and means for insulating said bolts from said angle-plates.

3. In a rail-joint, a base-plate having a recess at one end extending longitudinally thereof beyond the line of abutment of the 60 rail-ends, and having a hole in such recess, a shim of insulating material matching to and received in said recess, a pin rigid with and depending from said shim received in said hole, angle-plates secured to said 65 base-plate at the side margins of the latter, insulating cheek-pieces between said angle-plates and sides of such rail-ends, bolts extending transversely through said angle- 70 plates, cheek-pieces and rail ends, and means for insulating said bolts from said angle-plates.

In testimony that I claim the invention above set forth I affix my signature, in presence of two witnesses.

ANDREW J. NEAFIE.
